United States Patent Office

Des. 181,717
Patented Dec. 17, 1957

181,717

DECANTER

Ernest L. Du Pree, Weston, Conn.

Application August 27, 1957, Serial No. 47,517

Term of patent 14 years

(Cl. D58—6)

I claim:

The ornamental design for a decanter, as shown and described.
